UNITED STATES PATENT OFFICE.

JOHN S. DAVIS, OF CLEVELAND, OHIO.

GRAIN-BINDING HARVESTER-FRAME.

SPECIFICATION forming part of Letters Patent No. 392,721, dated November 13, 1888.

Application filed July 5, 1887. Serial No. 243,315. (No model.

To all whom it may concern:

Be it known that I, JOHN S. DAVIS, a citizen of the United States, residing at Cleveland, in the county of Cuyahoga, State of Ohio, have 5 invented certain new and useful Improvements in Grain-Binding Harvester-Frames, of which the following is a description.

My invention relates to grain-binding harvesters of the class known as "low-down" or 10 "platform" binders, in which the grain is gaveled and bound on or substantially on the level of the platform in rear of the main wheel, and it relates to such improvements in the details of construction and assembling of the 15 parts of the wheel, platform, and binder frames as to produce a very strong, light, and compact machine; to the devices for adjusting the wheel and platform frames relatively to each other; to improvements in the driving mechanism and shafts for transmitting motion to the binding mechanism, platform-carrier belts, and cutter sway-bar; to the trailing or rear 20 caster-wheel, whereby it may be automatically locked against swinging when the machine is traveling in a straight line and unlocked at the 25 pleasure of the attendant, and to other details, as will hereinafter be fully set forth.

In the accompanying drawings, which illustrate my invention in the best form now known 30 to me, Figure 1 is a general plan view of so much of a harvester as is essential to a proper understanding of my invention, some of the parts being broken away for the purpose of better illustration. Fig. 2 is a side elevation 35 of the same as seen from the stubble side of the machine. Fig. 3 is a view, partly in section, on the line 3 3 of Fig. 1, showing a rear elevation of the binder gear-plate, finger-beam, sway-bar, reel-post, &c. Fig. 4 is a rear elevation of the binder-frame, partly in section, 40 on the line 4 4 of Fig. 1. Fig. 5 is a view of the rear end of the binder-frame and the rear side of the platform, the caster-wheel being omitted from its forked support. Fig. 6 is a 45 side elevation of the inner binder-frame bar and top rail with the tilting bar or handle rigidly attached thereto. Fig. 7 is a view, partly in side elevation and partly in section, on the line 7 7 of Fig. 1, of a portion of the main wheel and its surrounding frame; and Fig. 8 is a rear elevation of the same, partly in vertical transverse section, on the axial line of the main

wheel. Fig. 9 is an enlarged detail view of the outer sill-bar of the binder-frame and parts attached thereto. Fig. 10 is a rear elevation 55 of the casting or bracket which connects the rear platform-sill bar to the binder-frame. Fig. 11 is a plan view of the same, showing also the loop-bracket in the inner binder-sill bar, through which the pitman plays. Fig. 60 12 is a plan view of the outer hanger or box of the main-wheel axle. Fig. 13 is a plan view of the front outer corner of the wheel-frame, partly in section on the line 13 13 of Fig. 7, and with the cap of the driving-gear box removed. Fig. 14 is a detailed sectional view 65 of the pinion and sliding clutch-sleeve on the main line shaft. Figs. 15 and 16 are views of opposite sides of the loop-bracket of the inner binder-sill bar. Fig. 17 is a view in rear elevation 70 of the tie-piece or bracket which unites the rear upturned parts of the binder-sills, and is provided at its outer projecting end with a suitable bearing for the caster-wheel, fork, &c. Fig. 18 is a sectional view of the same on the 75 line 18 18 of Figs. 17 and 19. Fig. 19 is a plan view, and Fig. 20 a vertical section, of the same on the line 20 20 of Fig. 19. Fig. 21 is a view of the caster-wheel-locking latch or bolt detached. Fig. 22 is a transverse section of the platform on the line 22 22 of Fig. 1. Fig. 23 is an enlarged plan view of the sway-bar and the reel-supporting connections 80 on the platform. Fig. 24 is a longitudinal section of the sway-bar, &c., on the line 24 24 of Fig. 22. Fig. 25 is a detailed side elevation 85 of the sleeved bearing for the sway-bar, and Fig. 26 is a plan view of the same. Figs. 27, 28, and 29 are respectively plan view, side elevation, and vertical central section of the post or stud-bearing of the sway-bar. Figs. 30 and 31 show a modification of my caster-wheel-locking device.

The driving-wheel A of my harvester is surrounded by a U-shaped frame, A' A², bent 95 across the front of the wheel and suspended from the main axle A³ by brackets A⁴ A⁵ of the frame. A bar, A⁶, extending parallel to the other bars and bent at right angles to cross the front of the U-shaped frame, to which it is 100 secured by bolts and overlapping clip-brackets a a', forms an outer compartment of the main or wheel frame, within which is mounted the gear bed or bracket B, the binder gear-plate C,

and the line-shaft D, through which motion is communicated to the harvesting mechanism. At its front inner corner the bar A⁶ forms a lug, a², between which and a corresponding lug on the clip a the heel of the tongue E is pivoted on a bolt, e. A brace-bar, E', is bolted to the tongue, and, extending diagonally, is pivotally connected to the frame in axial line with the bolt e by means of a clip-bracket, a³, 10 and a bolt, e'. The foot-board E² is bolted on top of the tongue near its heel, and, extending outwardly, is secured to the brace-bar E' by a bracket, e², and upon it is mounted the seat spring or standard E³. The three bars A' A² 15 A⁶, constituting the main frame, are pivotally connected to the platform at their rear extremities to form a hinged connection.

The gear-box B is formed, as shown, to afford suitable bearings for the counter-shaft B' 20 and line-shaft D to protect the bevel-gears B² B³ and sliding clutch B', and to stiffen and strengthen the wheel-frame, to the bars A² A⁶ of which it is securely bolted at the points shown, and it is provided with a suitable cover 25 or upper half.

In order to reduce the weight of the harvester to the lowest practicable point, I use in its construction very light bar-iron, and strengthen the wheel-frame by the tie-rods or 30 braces, as follows: The brackets or hangers A⁴ A⁵ are secured to the frame-bars A' A² by bolts and overlapping-ledges, as shown, and, extending upward, terminate in long sleeve-bearings for the axle A³. On the top of each of these 35 bearings is cast a double lug, f, through which pass tie-rods f' f², the latter extending back and attached by bolts to the frame-bars near their rearward extremities, and the former extending forward and passing through depending lugs on the clip-brackets a a' on the front of the frame. By means of screw-nuts the tension of these rods may be adjusted at pleasure, and the side bars of the frame relieved of the 40 weight of the machine and all twisting strains 45 from the hangers.

The inner tie-rod, f', transmits the pulling strain of the tongue directly to the inner end of the axle, and a tie-rod, f², from the base of the hanger A⁵ to the tongue-brace bracket a³, 50 transmits the strain directly to the outer end of the axle, thus relieving the frame and gear-box B from the twisting strains of the tongue and preventing any cramping of the counter-shaft B'. A rod, f⁴, from the base of the 55 hanger A⁵ to the frame-bar A⁶, is provided with clamping-nuts at each end and braces the frame-bars strongly at this point, while a diagonal tie-rod, f⁵, from the top of the hanger A⁵ to the bar A⁶, transmits a portion of the 60 load from that bar to the axle. The main driving-wheel and a sprocket-wheel, P, for driving the reel are pinned or keyed to the axle A³ and prevent its longitudinal movement through the hanger-sleeves, while a head, a⁴, 65 on the outer end of the axle prevents the hanger A⁵ from being pulled endwise on the axle by the strain of the rod f⁵.

It will readily be understood from the foregoing description that while I use very light frame-bars I can by the system of bracing employed produce a very light but strong and rigid wheel-frame, and by means of the nuts on the truss-rods I can without difficulty secure a very nice adjustment of the gearing and working parts of the machinery. 70

The platform-frame consists of the finger-beam G, of angle-iron, and a wooden rear bar, G', connected by bottom boards in the usual manner, the outer board, G², or that nearest the stubble end of the platform, being much 80 thicker and heavier than the others to strengthen the platform and carry the sway-bar, as will be hereinafter described.

Brackets H' H² H⁶, attached to the finger-beam, are pivotally connected to the rear ends of the wheel-frame bars A' A² A⁶, respectively, as shown. The bracket H' is securely bolted to the front face of the finger-bar, and has a flange or foot which extends beneath the bottom board, G², to which, and also to the bottom flange of the finger-beam, it is bolted, as shown. From the finger-beam it extends forward like a shoe, and has two ribs or ears, h, formed on its upper surface, between which the end of the wheel-frame bar A' is pivoted. 90 A projecting table, h', is also formed on this bracket, upon which is bolted a bearing-box, p, for the reel-driving counter-shaft P'. Another bracket, H, is secured to the finger-beam and bottom board in a manner similar to that just described, and extends forward to form a table or rest, h², upon which is secured a bearing-box, p'. At the inner end of the table stands a lug, h³, from the inner face of which projects a stud-pin, h⁴, upon which the foot of the reel-post P² is mounted. The brackets H² H⁶ are each bolted to the sill-bars I J of the binder-frame, and have depending feet, which are similarly attached to the finger-beam, while at their front ends they are formed with offset lugs, between which and the sill-bars the wheel-frame bars A² A⁶ are pivoted. 100

The binder-frame sill-bars I J extend transversely across the platform near its outer end, and are connected near their front ends to the finger-beam, upon which they rest edgewise, by means of the brackets H² H⁶, just described, and clamping-bolts g, which hook over the sill-bars, and, passing through the finger-beam, are provided with screw-nuts bearing against its under face. These bolts form a very strong connection and relieve the brackets of heavy strains. The outer sill-bar, J, extends in advance of the finger-beam, and has one side of the gear-plate C bolted to it by a depending 110 foot, c, while its rear end is upturned and extends forward over the binding-receptacle, terminating at a metallic bracket, K, to which it is rigidly attached. The inner sill-bar, I, also projects slightly in advance of the finger-beam, 115 from which it extends straight back to the rear bar of the platform, where it is upturned and forms a rail, I', which, returning over and to the front of the binding-receptacle, is there 120 125 130

turned down and bolted to the front end of the sill in advance of the finger-beam. At the point where the sill-bars cross the back bar, G' , of the platform they are each bolted to the 5 feet l of a strong metal bracket, L , which in turn is firmly secured to the bar G' by means of its upright ears l' , and has formed in it journal-box l'' for the line-shaft D .

In designing my machine the several parts 10 are located to produce their best individual results, and this incidentally brings the sill-bar I directly in line with the sway-bar M on one side and the crank-shaft D on the other, and therefore across the path of the connecting-pitman N . A bent pitman was first used 15 to get around this obstacle; but in practice I found it open to such strong objections that I invented the following device to permit of the use of a straight pitman:

20 At a point in the rear of the back board of the platform where the path of the pitman is intersected by the sill-bar I a portion of the latter is cut out and the gap thus formed bridged over by a looped casting, N' , securely bolted to the adjacent ends of the sill-bar and the rail I' and by a flanged projection, n , to the platform back bar, G' .

The bracket K , which spans the space between the upper portions of the sill-bars, to 30 each of which it is firmly bolted, is formed to afford bearings at suitable points, k k' , for the packer and needle-arm shafts, respectively, of my binding mechanism. (Not herein shown.) The latter bearing is formed in a portion, K' , 35 of the bracket which projects outside of the plane of the sill-bar, and is connected by a brace-bar, J' , to the binder gear-plate C . This gear-plate is a light skeleton frame suitably shaped, as shown, to afford bearings for and 40 support the several working parts mounted thereon, and at its inner edge is securely bolted to the front upright portion of the binder rail-bar I' . It will be observed that the gear-plate is mounted upon the binder-sills in advance 45 of the pivotal connection of the wheel and platform frames, and that it is located entirely outside of the main wheel and in advance of its rear edge.

As most of the weight of the binder resides 50 in the gear-plate and the mechanism attached directly thereto, and as this weight is brought by the described construction and location to a point near the main axle, it will be so nearly counterbalanced thereon by the weight of the 55 driver and the tongue in front of the axle that the vertical adjustments of the finger-beam may be readily effected by means of the direct-acting lever O , rigidly connected to the binder-frame. This lever is connected to the front 60 upper corner of the inner rail, I' , in such manner as to form a diagonal brace across the corner, and thereby stiffen the frame. From this point of connection it extends forward to a position in advance of the main axle within 65 easy reach of the driver in his seat, and is provided with a guard block or strap, o , which forms a loop for the rack-bar O' and a housing

for a spring-detent bolt, o' , controlled by a finger-piece, o'' , at the handle. The rack-bar O' is pivoted concentrically with the main 70 axle upon the sleeve of the hanger A^3 , and is provided with notches into which the detent-bolt takes to lock the machine against downward flexure.

When the cutter-bar is lowered from the 75 position shown in Fig. 2, the upper corner of the binder-frame pitches forward and downward toward the main axle; but the rack-bar O' , being pivoted, swings forward to compensate for the movement of the binder-frame 80 and lever, and thus maintains nearly the same right-angle relation to the lever that is shown in Fig. 2.

The knotter box or casing Q , securely bolted at its front end to the gear-plate C , is supported at its rear end upon a bracket, Q' , securely bolted to it and to the sill-bar J . As several portions of the binding mechanism subjected to heavy pressures or strains are mounted upon shafts which have bearings in 90 knotter-box and the bracket, I brace and strengthen them as follows: At the forward end of the box I attach, to any suitable point on its outer edge, a brace-bar, q , which extends to the overhead frame-bar J' and, being bolted thereto, braces the overhanging side of the box. A diagonal brace-bar, q' , attached near the bottom edge of the box at its rear end, and to the bracket Q' near the sill-bar, supports the overhanging rear end of the box. A brace, 95 q'' , attached to the inner side of the box above the finger-beam, extends diagonally down to and is securely bolted to it at a point near the inner shoe, H' . The lower portions of the 100 sill-bars are securely tied together midway between the platform front and rear bars by a brace-rod, i , while a brace rod, j , extending from near the top of the bracket Q' to the inner sill-bar, I , firmly holds the rear end of the knotter-box against outward thrusts or strains. 105 The upper portions of the sill-bars and the bracket K are further secured by a brace-rod, k^2 , above the latter, while a brace-rod, k^3 , extending from the outer top corner of the gear-plate to the upper front corner of the rail-sill 110 I , strengthens the frame at these points. 115

A guard bracket, or shoe, J^2 , attached to the sill-bar, J , serves to protect the downwardly-projecting horns of a pair of cut-off arms, (not shown,) from contact with any 120 obstacle on the ground, and also acts as a strut for the truss-rod j' , attached to the sill-bar near the extremities of its lower portion. As shown in the drawings, this rod j' is secured directly to the sill bar at its point of attachment with 125 the rear platform-bar, while its front end passes through an ear or lug, c' , on the gear-plate, and is provided with a screw-nut to hold it and regulate its tension. The reel-post P^2 is mounted upon the stud-pivot h^4 , as before 130 mentioned, and a driving-chain connects the sprocket-wheel p^4 of the reel-shaft P^3 with a similar wheel, p^4 , on the counter-shaft P' , which is in axial line with the stud h^4 , so that the in-

clination of the post may be changed without affecting the driving-chain. Upon the shaft P' is another sprocket-wheel, p^5 , connected by a driving-chain with the sprocket-wheel P on the main driving-axle, and as the shaft is substantially in line with the pivotal connections of the wheel and platform frames the length of this latter chain will not be affected by the vertical adjustments of the finger-beam.

10 A brace rod, P⁴, extends diagonally from near the head of the reel-post to the rail I' of the binder-frame, to which it is secured by a bolt passing through any one of the series of holes i', by means of which the head of the 15 reel-post may be adjusted back and forth.

The line driving shaft D is mounted in suitable bearings in the casting L in the rear of the platform, the gear-plate C of the binder-frame, and the gear-box B of the wheel-frame, 20 and is provided between the last two bearings with a tumbling shaft having universal joints at each end and a telescoping section to permit of the varying angles and lengths due to adjustments of the height of the cutter-bar. On 25 the shaft between the front and back bars of the platform are mounted rollers d, which drive the platform-carrier belts d', and at its projecting end, in rear of the back platform-bar, is the crank-plate D', connected by a pitman, N, with the sway-bar M, which at its 30 front end is connected by a short pitman, R, to the cutter-bar R', as shown. The sway-bar is of wood, and is provided at its rear end with a metallic cap or socket, N², formed with a 35 wrist and ball for the attachment of the pitman. This socket, as will be seen by Figs. 22, 23, and 24, slips over the end of the sway-bar, inclosing it on all sides, and is held thereon by a transverse bolt passing through the bar and 40 the two side ears, n², of the socket, which extend along its sides. The sway-bar vibrates in a slot in the back bar of the platform and above the finger-beam, and is supported at a proper point within its length on a vertical 45 pivot constructed as follows, (see Figs. 3 and 22 to 29, inclusive:)

A hollow cylindrical pivot post or stud, m, has a wide base provided with depending lugs m' at each side. These lugs are fitted snugly 50 into recesses in the heavy bottom board, G', of the platform and with the aid of bolts m² hold the post in position. A cylindrical sleeve-bearing, m³, fitting upon this post passes through an aperture in the sway-bar, and is 55 secured by a flanged projection, m⁴, which fits against the under side of the bar, and is secured thereto by bolts, as shown. A strap or yoke-piece, m⁵, rests upon the top of the pivot-post above the bar, and is held in place by a bolt, 60 m⁶, passing through the strap, post, and bottom board, and firmly clamped by a nut on the under side. The strap extends beyond the sides of the sway-bar, and is then bent down and terminates in feet m⁷, which rest upon the 65 bottom board and are rigidly bolted thereto. This forms a strong firm pivot post for the

sway-bar, and one well calculated to resist the side thrusts to which it may be subjected.

The rear side of the platform and binder-frames is supported on a caster-wheel, S, in a 70 similar manner to that shown in my grain-binding harvester patent, numbered 312,824, granted February 24, 1885; but I have made several improvements in the details of construction of the caster-wheel which materially 75 improve its operation.

The location shown in Fig. 1 of the several parts of my harvester places all the heavy weight of the binding mechanism outside of the path of the main wheel and well forward, 80 so that it nearly balances the platform and grain-wheel on the inside of said path, while the weight of the tongue and driver in advance of the main axle largely counterbalance the mechanism in the rear of it. Owing to this 85 concentration of weight on the main wheel, and the fact that the machine is nearly balanced across its path, I place the caster-wheel at the outer rear corner of the platform and close in to the binder-frame. When the harvester is running straight forward and the 90 caster-wheel is trailing in a straight line, the machine is in its most perfect condition of balance, the load resting mainly on the main and caster wheels with just sufficient weight on the 95 grain-wheel at the inner end of the platform to keep it firmly on the ground and insure the stability of the machine. In order to preserve this condition when the machine is working along a hillside with the platform on the 100 high ground, I lock the caster-wheel against yielding to the natural tendency of the machine to slide down the hill and hold it in its straight trailing position. As the equilibrium 105 of the machine under the hillside condition just described depends largely upon this wheel, it will be readily understood that if it were free to swing in toward the path of the main wheel, which the downhill-drifting tendency of the machine would cause it to do, the 110 grain end of the platform might be lifted from the ground and the machine upset.

Another and even more important advantage of locking the wheel against swinging is that it absolutely prevents the side thrashing 115 of the tongue against the horses caused by the grain-wheel passing over uneven ground.

While under every condition of "straight-away" work it is desirable to lock the caster-wheel, it is necessary that it should swing 120 freely when the machine is to be turned, so I have arranged a latch that will automatically engage and lock it when the machine is drawing straight, but which may be unlocked by the driver from his seat for turning or any 125 other purpose.

A metallic bracket, T, is securely bolted to the rear upright portions of each of the binder-sill bars and, projecting beyond or outside of the sill J, terminates in a tubular sleeve or 130 bearing, T', for the shank of the caster-wheel fork S, to the upper end of which is keyed a

rearwardly-extending lever, S^2 , notched at its end s , and having the lower sides of the forks s' at each side of the notch inclined or sloping to a common center. An arm or lug, T^2 , projecting from the top of the sleeve-bearing and strongly braced from the main body of the bracket, is perforated at a point immediately below the normal position of the notch in the lever for the passage of the locking-bolt t' , which projects through it and takes into the notch. This bolt is formed on the end of an arm of a bell-crank lever, T^4 , pivoted between ears t' on the bracket and provided with a spring, t' , which urges the bolt into its locking position. To the depending arms t' of the bell-crank is attached a wire cord or other suitable flexible connection, t^5 , which passes through an aperture in the lower edge of the bracket and around guide-rollers j^2 j^3 on the sill-bar J . Near the lower roller it is attached to a rod, T^5 , guided in bearings t^5 , secured to the sill-bar, near the former of which the rod is jointed about in line with the hinged joint between the platform and wheel frames. From this joint it extends to the depending arm of a bell-crank or the latch T^6 , mounted on the foot-board within easy reach of the driver in his seat. When he desires to "go about," he depresses the latch T^6 with his foot and withdraws the locking-bolt that holds the caster-wheel lever, leaving the wheel free to swing to right or left, as the case may be. He can then remove his foot and allow the bolt to resume its normal position, the sloping forks s' on the lever riding over and depressing it when the wheel is swinging back; but when it reaches its normal trailing position the bolt springs up into the lever-notch s .

The back board, G' , extends from the end of the platform to the inner sill-bar, I , of the binder-frame, and is supported by a piece, G^3 , let into its upper edge and securely held in place by bolts g' extending through the bar G' , and by bolts g^3 in the yoke and sill-brace castings N L . The bottom boards are securely fastened to the under side of the back board or beam along its length, while a diagonal brace, g^3 , extending between the heavy bottom boards, G , and the back board, stiffens the corner joint.

In order to prevent any possibility of the finger-beam G being twisted or pulled out of shape at its top edge by the draft at the point of connection of the main frame-bar A' , I connect it to the rear beam or bar, G' , by a tie-rod, g^4 , extending across the platform directly in the line of draft, attached to the finger-beam near its upper edge and to the back board at or near the brace g^3 , so that the pulling strain is resisted by or taken up in the bottom board.

Instead of positively locking the caster-wheel fork against turning until released by the driver, as hereinbefore described, it might be advantageous at times to have it unlock automatically when subjected to unusual or excessive pressure. This may be accomplished by the construction of parts shown in Figs. 30 and 31,

in which the lever-arm S^2 has a pocket or recess, s^2 , formed in its under side near the rear end, instead of being slotted or notched, as before described. The bolt t' lies in this recess, the side walls of which are inclined like the outer edges of the lever to depress or force down the bolt when the lever swings across its path; but their inclination is much steeper than is that of the outer edges, and it would consequently require a much greater side force of the lever to force the bolt down by the inner walls.

What I claim, and desire to secure by Letters Patent, is—

1. The wheel-frame of a harvester divided into two compartments, the inner or wheel compartment formed by a single bar composing its sides, A' A^2 , and closed front end, the outer compartment formed by a bar, A^6 , running parallel to the bars A' A^2 , then turned at right angles at its front end to lap across the closed front end of the inner compartment, to which it is rigidly bolted, substantially as shown and described.

2. The combination of the L-shaped bar A' A^2 , forming the inner compartment of the wheel-frame, the L-shaped bar A^6 , forming its outer compartment and lapping across the closed front end of the inner compartment, the clip-bracket a , embracing both bars at their edges and bolted thereon, the ear on the bracket and the foot a^2 on the bar A^6 , with the tongue and its pivot, substantially as hereinbefore set forth.

3. The combination of the side bars, A' A^2 , of the wheel-frame, the bearing-brackets A^4 A^5 , the main wheel and its shaft mounted in the brackets, and truss-rods f' f^2 , attached to the front and rear ends of the frame, respectively, passing through perforations at the top of the bearing-brackets, and provided with adjusting-nuts, as and for the purpose hereinbefore set forth.

4. The combination of the wheel-frame, the driving-wheel and its shaft journaled in fixed brackets A^4 A^5 , attached to the side bars of the wheel-frame, the tongue pivotally connected to the front inner corner of the wheel-frame, and the inner truss-rod, f' , passing directly from the pivot-bracket at the heel of the tongue through an aperture in the top of the bracket A^4 , with means for adjusting its length, substantially as hereinbefore set forth.

5. The combination of the wheel-frame bars A' A^2 and the bearing-brackets A^4 A^5 mounted thereon, the frame-bar A^6 , and the brace-rods f^4 f^5 , substantially as hereinbefore set forth.

6. The combination of the wheel-frame bars A' A^2 and the bearing-brackets mounted thereon, the main shaft provided with a head, a^4 , on its outer end, the main-wheel hub keyed to the shaft between the bearings to firmly hold it against endwise movement therein, with the frame-bar A^6 and the brace-rod f^5 , substantially as and for the purpose hereinbefore set forth.

7. The combination of the driving-wheel, its

shaft, and the bearing-brackets attached to the middle of the frame-bars A' A², the tongue, with the driver's seat mounted thereon, and the gear-box B, attached to the front side of the frame, and the platform and binder-frame attached to the rear end of the frame-bars, with the truss-rods f' f' f² f², attached to the frame at its front and rear ends, respectively, and in line with hanger-bearings, to the tops of which they are also attached, substantially as hereinbefore set forth.

8. The combination of the sill-bar I, the platform-frame to which it is rigidly attached, the loop-casting N', the rail I', beginning at the loop-casting and extending over the binding-receptacle to the front end of the sill-bar and firmly bolted thereto, substantially as hereinbefore set forth.

9. The combination of the binder-sill bars I J and the rail-bar I', secured at its front lower end to the sill-bar I, with the gear-plate C, attached by a depending foot at its outer lower corner to the sill-bar J and at its inner vertical side to the rail-bar I' at a point above the sill-bar I, substantially as and for the purpose hereinbefore set forth.

10. The combination of the binder-sill bar J and the gear-plate C, securely bolted to its front end, the binder-sill I, the rail I', bolted to the inner edge of the gear-plate and at each of its depending ends to the sill-bar I, the bracket K, connecting the rail I' and the upturned rear end of the sill-bar J, and the rail J', extending from the bracket K to the gear-plate, substantially as hereinbefore set forth.

11. The combination of the binder-sill J, attached near its ends to the finger-beam and the back bar of the platform, the guard-bracket J', and the truss-rod f', substantially as hereinbefore set forth.

12. The combination of the gear-plate, the overhead rail J', the sill-bar J, the knotter-box attached at its front inner corner to the gear-plate and at its rear inner corner to the bracket Q' from the sill-bar, and the brace-bar q from the overhanging edge of the box to the rail J', substantially as hereinbefore set forth.

13. The combination of the gear-plate, the sill-bar J, the knotter-box attached at its front inner corner to the gear-plate and at its rear inner corner to the bracket Q' from the sill-bar, and the brace-bar q', attached to the lower overhanging rear corner of the box and to the bracket Q' from the sill-bar, substantially as hereinbefore set forth.

14. The combination of the gear-plate, the sill-bar, the finger-beam, the knotter-box attached at its front end to the gear-plate and at its rear end to a bracket, Q', from the sill-bar, with the brace-rod q² from the upper edge of the knotter-box to the finger-beam, substantially as hereinbefore set forth.

15. The combination of the finger-beam and the binder-sill bars resting on its top, with the brackets H² H⁶, bolted to the front face of the finger-beam and to the sill-bars, as shown, and the hooked clamping-bolts, which catch

over the sill-bars passing through the beam, and are provided with nuts at its lower side, substantially as hereinbefore set forth.

16. The combination of the sill-bars, the knotter-box, the bracket Q', attached at its base to the sill-bar J, the brace-rod j from the top of the bracket to the sill-bar I, substantially as hereinbefore set forth.

17. The combination of the binder-sill bars, the back bar, G', of the platform terminating at the inside of the binder-frame, the extension G³, overlapping the top edge of the back bar and rigidly fastened thereto and extending across the binder-frame above the sill-bars, the bracket L, securely bolted to the sill-bars and to the extension-piece G³, as shown.

18. The combination of the back board G, and the extension-piece G³ secured thereto, the sill-bars I J, with the connecting-bracket L and the loop-bracket N', bolted to the back bar and its extension and to each other, substantially as and for the purpose hereinbefore set forth.

19. The combination of the inner binder-frame sill and rail I I', constructed substantially as shown, with the tilting lever bolted to the front upright portion of the rail, and from thence extending diagonally to its upper horizontal portion, to which it is also bolted, substantially as and for the purpose hereinbefore set forth.

20. The combination of the driving-wheel, the frame surrounding the same and rocking about its axle, the tongue pivotally connected to the front end of the frame, and the platform similarly connected to its rear end, the binder-frame mounted upon the platform on the stubble side of the driving-wheel, the easter-wheel at the rear outer corner of the platform and tracking outside of the main wheel, and the tilting lever rigidly secured to the binder-frame, substantially as hereinbefore set forth.

21. The combination of the binder-frame sill-bars, the bracket T, and the easter-wheel, with its locking device, hereinbefore described, a tripping-latch within reach of the driver in his seat, a flexible connection from said locking device to the trip-latch passing over guide-rollers on the binder-sill bar in such manner as to be conducted below the plane of the binding-receptacle, substantially as hereinbefore set forth.

22. The combination of the binder-frame sill, the crank-plate, and the sway-bar in substantially the same plane, the pitman connecting the crank and the sway-bar, and the looped bracket in binder-frame sill, substantially as hereinbefore set forth.

23. The combination of the finger-beam and the back board of the platform, the heavy bottom board, G², and the tie-rod g⁴, connecting the finger-beam and back board above the bottom board, G², substantially as hereinbefore set forth.

24. The combination of the finger-beam and the back board of the platform, the heavy bottom board, G², the main-frame bar A', connected

to the finger-beam, the tie-rod g^1 , connecting the finger-beam and back board above the bottom board, G^2 , in the line of draft of the frame-bar and the brace g^3 from the back to the bottom board, substantially as and for the purpose hereinbefore set forth.

25. The combination of the bottom board, G^2 , the pivot-post m and its base-plate provided with depending lugs m' , which take into recesses in the bottom boards, and the bolts m^2 , for rigidly attaching the post to the board, substantially as hereinbefore set forth.

26. The combination of the bottom board, G^2 , the hollow pivot-post, the sleeve-bearing mounted on the post, the sway-bar secured to the sleeve, the strap or yoke-piece m^3 , extending across the sway-bar and pivoted and secured at each side thereof to the bottom board by its depending feet m^4 , and the tie-bolt m^5 , passing through the strap, pivot-post, and bottom board, substantially as hereinbefore set forth.

27. The combination of the counter-shaft,

the stud h^1 in axial line therewith, the reel-post mounted thereon, the reel-shaft, the 25 sprocket-wheels $p^3 p^4$, connected by a driving-chain, the brace-bar P^1 , and the binder-frame bar I' , having a series of holes, i' , for the purpose hereinbefore set forth.

28. The combination of the main wheel and 30 its axle, the wheel-frame rocking about the main axle, the platform pivotally connected to the rear end of the wheel-frame, the brackets $H H'$, secured to the platform, and the counter-shaft P' , supported in bearings thereon substantially in line with the pivotal connection of the wheel-frame and platform, the sprocket-wheels $P p^5$, connected by a driving-chain, substantially as and for the purpose hereinbefore set forth.

In testimony whereof I hereto affix my signature in presence of two witnesses.

JOHN S. DAVIS.
